UNITED STATES PATENT OFFICE.

CHARLES HARRY COBB, OF SAN FRANCISCO, CALIFORNIA.

RADIATOR SUPPORT.

Application filed September 7, 1923. Serial No. 681,451.

To all whom it may concern:

Be it known that CHARLES HARRY COBB, a citizen of the United States, residing at San Francisco, in the county of San Francisco and State of California, has invented new and useful Improvements in Radiator Supports, of which the following is a specification.

Radiators now in use are supported upon legs resting on the floor which necessitate the laying of floor boards prior to the installation of the radiators and which also make it difficult in laying or removing carpets or rugs.

It is, therefore, the purpose of the present invention to obviate these difficulties and to provide a radiator support so that the radiator may be arranged at any desired elevation to permit of the insertion of rugs, carpets and the laying of floor boards under the radiator after the installation of the radiator and so that the radiator may be disposed at any desired elevation to accommodate special or unusual heights of base boards.

Another purpose is to provide, in a support of this kind, a construction which shall support the weight of the radiator entirely from the wall under conditions which do not involve a shearing strain to the anchor bolts or other anchoring means by which attachment may be made to the wall and which, therefore, are not subject to injury, displacement or failure regardless of the weight of the radiator.

A still further purpose is to provide, in a radiator support, a construction wherein the radiator support proper is capable of adjustment for accommodating the support proper to the spaces between the coils of the radiator, so that the radiator may be properly supported spaced relatively both with the floor and the wall to permit of cleaning under and behind the radiator.

It is to be understood that the particulars herein given are in no way limitative and that, while still keeping within the scope of the invention, any desired modifications of detail and desired proportions may be made in the apparatus according to the circumstances.

The invention comprises further features and combination of parts to be hereinafter set forth, shown in the drawings and claimed.

In the drawings:

Figure 1 is a view in front elevation of a portion of a radiator, showing the support applied, a portion of which being in dotted lines.

Figure 2 is a vertical sectional view through a wall, showing the upper and lower supports in side elevation.

Figure 3 is a vertical sectional view through the lower support.

Figure 4 is a detail plan view of a portion of a radiator, more clearly showing the upper support.

Figure 5 is an enlarged detail view of the base bracket of the lower support.

Figure 6 is a detail view of the radiator support proper which connects with said base bracket.

Referring to the drawings, 1 designates a suitable wall, and 2 and 3 anchor bolts which engage through the wall and are anchored therein in the usual manner. The upper anchor bolt 2 passes through an elongated slot 4 of an angle plate or bracket 5, the perpendicular portion 6 of which has a slot 7 which receives the shank of the bolt 8. The perpendicular portions of the angle plate terminate in lugs 9 which extend toward the wall. The adjacent surfaces of the slot 7 immediately close to the lugs 9 have opposed protrusions or lugs 10 which overlie one of the faces of the nut 11 which is threaded upon the bolt 8 to prevent accidental displacement of the nut.

The angle bracket or plate 5 adjacent the perpendicular portion 6 has lugs 12 which engage the adjacent portions of two coils of the radiator, thereby acting to prevent lateral movement of the radiator when disposed in position. The slot 4 is provided for the purpose of permitting the angle bracket or plate to be adjusted, whereby it may accommodate itself to the construction and arrangement of the coils of the radiator.

The bolt 8 passes through a cupped plate 13 which is of tapering contour to fit between two adjacent coils of the radiator. The head of the bolt engages in the depressed seat 14 of the cupped plate and by tightening up on the screw, the radiator may be drawn closely in engagement with the angle bracket or plate.

The lower radiator support comprises a bracket 15, an extension 16 of which receives the shank of the anchor bolt 3. The rear

face of this bracket is cut away, causing a recess 17 to be formed. The front face of the bracket 15 is provided with longitudinal perpendicular side flanges 18, the upper ends 5 of which are integrally united by means of the projecting ear or lug 19 which has an elongated slot 20.

The rear face of the bracket 15 has a boss 21 which engages a depression 22 in the wall. 10 This boss has a screw-receiving opening 23 which receives a screw for securing the bracket 15 in position. The head of the screw, which passes through the boss, is countersunk in the face of the bracket 15.

15 An elongated supporting bolt or screw 24 has its shank passing upwardly through the slot 20 and is supplied with a nut 25. This supporting screw also engages through a sleeve 26, the forward portion of the wall 20 of which has a supporting arm 27, preferably integral with the sleeve. This supporting arm is of reinforced web construction and is of arcuate shape to engage under the pipe connections 28 which connect the coils 25 of the radiator, thereby supporting the radiator in position.

The upper end of the sleeve has a webbed arm 29 which extends upwardly and rearwardly and terminates in lateral lugs 30. 30 The sleeve 26 is located centrally between the side flanges of the bracket 15 and spaced from the front face of the bracket, so that the webbed arm 29 may extend rearwardly and upwardly and be located between the side flanges of the bracket, whereby the lateral lugs 30 may engage with the undercut or recessed portion of the bracket 15. The lower portion of the sleeve 26 terminates in a rearwardly projecting lug 31 provided 35 with a foot 32 which engages the lower portion of the front face of the bracket 15 at a point between the lower ends of the side flanges of the bracket.

It is obvious that to support a radiator, it 45 is necessary to have two upper angle brackets or plates 5 and two lower brackets 15. It is just possible that these brackets, when ap-

plied, will not assume their proper spaced positions in order that they may connect with the radiator between its coils, hence the provision of the slots 4 and 20. The slot 4 permits of adjustment of the angle bracket or plate 5, so that its operative connection with the radiator between certain of its coils may be procured. The slot 20 in the forwardly projecting lug or ear 19 is provided for the purpose of permitting the bolt to be adjusted in order to support the sleeve 26 in such wise that the radiator supporting arm 27 may engage between certain of the coils 60 of the radiator to support the lower end of the radiator.

The invention having been set forth, what is claimed is:

A support for radiators including a 65 bracket adapted for anchorage to the face of a wall, a radiator support proper operatively connected to the bracket for lateral adjustment relative to the bracket whereby the radiator support proper may accommodate 70 itself to the division spaces between the coils of the radiator, a support operatively connected to the upper portion of the radiator and adapted for arrangement and connection with the wall, said radiator support 75 proper comprising a sleeve having means at its lower portion to bear upon the front face of the bracket to hold the sleeve spaced therefrom, the upper portion of the bracket having a forwardly protruding lug provided 80 with an elongated slot, a bolt passing through the slot and sleeve to permit the sleeve to be adjusted laterally, and means for anchoring the bolt in place, said bracket having its rear face provided with a recess 85 or cut away portion, the upper end of the sleeve having a rearwardly projecting arm provided with lateral lugs engaging with the recess or cut away portion to permit the sleeve with its bolt to be adjusted laterally. 90

In testimony whereof he affixes his signature.

CHARLES HARRY COBB.
